ADJUSTABLE LENGTH TAIL PIPE FOR OIL FIELD OPERATIONS

Gene D. Thompson, Houston, Tex., assignor, by mesne assignments, to Jersey Production Research Company, Tulsa, Okla., a corporation of Delaware

Application November 21, 1957, Serial No. 697,987

1 Claim. (Cl. 166—138)

This invention relates generally to apparatus for use in oil field operations, and more particularly to a variable length tail pipe or anchor pipe for use in conjunction with a well packer.

A conventional type of well packer includes an expandable, compressible, generally cylindrical member of rubber or rubber-like material connecting together two sections of pipe, the upper section of which may be a drilling string. The lowermost section of pipe may be adapted to abut against the bottom of a drill hole or to be supported by another packer or by sidewall anchoring means, so that when pressure is applied to the expandable, compressible member from the earth's surface or by the weight of the drill string through the other section of well pipe connected thereto, the member will expand to contact the side of the borehole with considerable force and effectively seal off a section of the borehole. The packer may be used in many operations, a common operation being drill stem testing; fluid entering the borehole beneath the packer can go to the earth's surface only through the pipe so that workmen at the earth's surface can obtain earth's fluids from the strata penetrated by the borehole.

In the course of setting the packer, often it is found impossible to obtain an effective seal using a given length of tail pipe. Therefore, it becomes necessary to vary the length of the tail pipe so that another attempt to obtain an effective seal may be made. Manifestly, it is undesirable to bring the packer to the earth's surface to connect a tail pipe of different length to the packer, or to adjust the length of the pipe connected to the packer by manual manipulations performed with the packer and tail pipe at the earth's surface.

In accordance with the teachings of the present invention, a pair of telescoping tail pipe sections are connected to the lower end of a flexible, expandable well packer. The position of the lower section is fixed within the borehole. In combination with the telescopic tail pipe sections, there is provided connecting means for selectively connecting and disconnecting the tail pipe sections responsive to manipulations of the drilling string from the earth's surface. Preferably, the manipulations are limited to raising, lowering, and rotating the drilling string, well packer, and the uppermost of the telescoping tail pipe sections.

A preferred embodiment of the invention utilizes a "slip cage" between the telescoping tail pipe members longitudinally movable with respect to the tail pipe members and carrying slips which are adapted to ride on an inclined surface of one of the tail pipe sections to engage the other tail pipe section and establish a strong mechanical connection between the two sections. Preferably, the mechanical connection between the tail pipe sections is established by the operation of setting down on the packer. The slips should be disengageable by picking up the drill string to disconnect the two tail pipe sections, to permit relative longitudinal movement

2

therebetween, and to permit adjustment of the overall length of the tail pipe when the packer is again reset.

A more complete understanding of the invention may be had from the following description thereof when considered with the accompanying drawings wherein:

Figs. 1, 2, and 3 are elevational views, partially in cross section, of a preferred embodiment of the invention in various successive operating positions thereof, and

10 Fig. 4 is a view of a portion of the inner of the telescoping tail pipe sections illustrating a slot therein which serves to actuate the slip cage shown in Figs. 1, 2, and 3.

With reference now to Fig. 1, there is shown a packer and tail pipe assembly with the various components 15 thereof in the positions that they will assume as they are being lowered into the borehole 2. Packer 3 may be a set-down packer as shown in U.S. Patent 2,661,064 to J. Rockoff. The packer itself may be constructed of steel-braid reinforced rubber or rubber-like material, 20 adapted to expand outwardly toward the sides of the borehole when a compressive force is exerted between the ends of the packer.

Retaining collars or shoes 13 and 14 couple the ends 25 of the packer to cylindrical pipe sections 1 and 4. Pipe section 1 may be connected to a drilling string in the usual manner. Mandrel 4 is one member of a telescoping tail pipe or anchor pipe assembly, the other telescoping section being identified by numerals 5 and 7. The end portions 5 of the outer or lower tail pipe 30 member permits insertion of the slip cage within the lower tail pipe member. O-ring 6 provides a seal between mandrel 4 and end portions 5. Outer tail pipe portions 5 and 7 are screw-threaded together as shown.

The lower end of outer tail pipe member 7 has a plurality of openings therein to permit free fluid communication between the borehole and the interior of chamber 35 when the tail pipe abuts against the bottom of the borehole or is anchored to the sidewall above the bottom of the borehole by suitable sidewall anchoring 40 means. In this manner, formation fluids from the borehole may freely enter the interior of pipe section 4. A small orifice 24 prevents the build-up of a differential pressure between chamber 33 and the borehole that could rupture tail pipe member 7. Chamber 33 may 45 be loaded with fluid to exclude drilling mud from the chamber as much as possible.

To rigidly connect the tail pipe sections 4 and 7 together, there is provided a slip cage assembly adapted to connect and disconnect sections 4 and 7 responsive to vertical manipulation of the drilling string. The slip cage assembly, which includes sections 15, 16, and 18, supports a plurality of slips 9. The slips 9 are adapted to ride up on a setting cone 8 so as to expand outwardly 55 to engage the inner surface of chamber 33. Setting cone 8 may be a portion of tail pipe section 4 or it may be a separate member friction fitted or otherwise securely affixed to tail pipe section 4 (for example, by a welding operation). Slip cage sections 15, 16, and 18 are annular members adapted to fit around the lower end 60 of tail pipe section 4 between setting cone 8 and lugs 23. Section 16 is positioned between sections 15 and 18 and carries a pin 12 adapted to engage a slot 20 within the tail pipe section or mandrel 4. The shape of groove 20 is 65 illustrated more perspicuously in Fig. 4, and its function will become apparent from the following discussion.

Slip cage sections 15 and 18 are connected together by a plurality of drag springs 11 which bow outwardly between the slip cage sections so as to engage the inner surface of tail pipe section 7. Four drag springs may be 70 provided which should exert sufficient force against the walls of chamber 33 to prevent free downward movement

of the slip cage responsive to gravitational force. An external force to reposition the slip cage may be applied through the packer and mandrel 4 by manipulation of the drill string.

Slip cage section 16 is freely rotatable and independent of the other sections 15 and 18.

While slips 9 are shown as being affixed to upper slip cage section 15, it is to be understood that they may be connected to the lower slip cage section 18, if desired.

The operation of the apparatus shown in the drawings is as follows: Let it be assumed that the packer and tail pipe assembly are being lowered into the borehole. The pin 12 should be in position A of Fig. 4. In this position the tail pipe section 7 will be suspended from or hanging on the upper surface of setting cone 8. The assembly is lowered into the borehole until the lower end of lower tail pipe member 7 touches the bottom. The drill string, packer 3, and mandrel 4 are lowered further until the lugs 23 on mandrel 4 strike the seal ring shoulder or wall 25. This will assure the operator at the earth's surface that the assembly is at the bottom of the borehole. Note that the pin 12 is still in position A.

After the lugs 23 strike the seal ring shoulder 25, the drill string 1, packer 3, and mandrel 4 are raised. Pin 12 is cammed horizontally by the edge of groove 20 to rotate section 16. Pin 12 will move along the groove until it is in position B (see Fig. 4). When pin 12 is in this position, the slip cage will be raised when the upper tail pipe section 7 and the pipe string are raised, until the packer is above the position at which it is to be set by a distance equal to the distance between points B and C on groove 20 (Fig. 4). The drill string, packer 3, and mandrel 4 are then lowered. The slip cage assembly will not move downwardly due to the restraining influence of drag springs 11. Pin 12 will move through slot 20 from position B toward position C until the slips engage conical surface 10 of setting cone 8. The slips will be biased outwardly by conical surface 10 until they engage the inner surface of chamber 33. Pin 12 will then be in position C as shown in Fig. 4. At this point, downward force may be exerted from the drill string which will force the slips to dig or bite into the wall of chamber 33 (see Fig. 3) so that there is a rigid mechanical connection between mandrel 4 and tail pipe section 7. The packer may now be set by application of more force thereto.

If the packer does not engage the side of the borehole so as to seal off the lower portion of the borehole, the drill string is picked up. As the drill string is raised, the packer is released to assume its normal shape, as shown in Figs. 1 and 2. The setting cone 8 is raised out of engagement with the slips and the slips should collapse to the position shown in Fig. 1. As the mandrel 4 moves up, the pin will move downwardly and will change from position C to position D, as shown in Fig. 4.

When the pin reaches position D, the slip cage will begin moving upwardly. If the slips tend to hang onto the wall of chamber 33, even after setting cone 8 has moved upwardly out of engagement with the slips, they will at this time be jarred loose and collapse to their normal position. The mandrel 4 can now either be raised or lowered to lengthen or shorten the overall length of the tail pipe. If it is desired to raise the mandrel, for example, into the position shown in Fig. 2, the pin 12 will remain in position D. However, if it is desired to lower the mandrel, pin 12 will move again to position A and the slip cage will move downwardly until it reaches the next position at which it is desired to try to set the packer. When the slip cage is in its new position, the drilling string and packer are lifted so that pin 12 will move into position B, and then the drill string and packer are lowered so that the pin is moved to position C to expand the slips and set the packer as described above.

It is to be noted that pin 12 can move in only one direction through the slot 20 in mandrel 4. The direction of movement is shown by the arrows in Fig. 4 and will follow the sequence of positions A, B, C, D, A. The shape of the slot is substantially the same as that of the slotted section in the so-called "Knowlton packer" manufactured by Knowlton Oil Tool Company, Los Angeles, California.

The invention described above permits a packer to be reset any number of times without the necessity of a round trip of the packer from the borehole to the surface. The operation for resetting the packer can be performed by workmen at the earth's surface almost entirely by raising and lowering the drill string. The apparatus as described is rugged, almost foolproof, and almost entirely void of maintenance problems.

The invention is not to be restricted to the specific structural details or arrangements of parts, as various modifications thereof may be effected without departing from the spirit and scope of this invention.

I claim:

In combination: a pipe string; a well packer including an expansible well packing member affixed to the lower end of said pipe string, said packing member being adapted to expand to the sides of a borehole responsive to longitudinal pressure exerted on said pipe string; a tail pipe for holding said packing member above the bottom of said borehole, said tail pipe including a first inner hollow, elongated tubular telescoping member connected to said packing member and a second hollow, elongated tubular telescoping member in telescoping engagement with said first telescoping member, said second telescoping member being adapted to abut against the bottom of the borehole; a wall within said second telescoping member defining an elongated chamber therein, said first telescoping member extending longitudinally through said second telescoping member and through said wall to provide fluid communication between the interior of said pipe string and the portion of said second telescoping member below said wall; a plurality of perforations in said second telescoping member below said chamber; a slip carriage within said chamber slidably mounted on said first telescoping member; said slip carriage including first upper, second intermediate, and third lower annular members in abutting relationship, all of said annular members being supported by said first telescoping member and longitudinally movable therealong, said second annular member being rotatable about said first telescoping member; a plurality of drag springs connecting together said first and third annular members, said drag springs being adapted to bias against the sides of the interior of said second telescoping member to restrain movement of said slip carriage responsive to gravity; a plurality of slips affixed to said slip carriage; a conical slip setting member affixed to said first telescoping member, said slip setting member being adapted to force said slips against the interior of said second telescoping member to rigidly connect together said first and second telescoping members; a slot in said first telescoping member defining a closed path, a pin in said second annular member fitting into said slot, said pin being adapted to move in a given direction around said path to successively move said slip carriage downwardly relative to said second telescoping member, to move said slip carriage upwardly relative to said second telescoping member, to move said slips into engagement with said slip setting member, and to disengage said slips from said slip setting member.
